CLAIM

The ornamental design for a ratchet wrench, as shown and described.

DESCRIPTION

FIG. 1 is a perspective view of a ratchet wrench in showing our new design;

FIG. 2 is a left side view of the ratchet wrench of FIG. 1; FIG. 3 is a right side view of the ratchet wrench of FIG. 1; FIG. 4 is a top view of the ratchet wrench of FIG. 1;

FIG. 5 is a bottom view of the ratchet wrench of FIG. 1; FIG. 6 is a back view of the ratchet wrench of FIG. 1; and, FIG. 7 is a front view of the ratchet wrench of FIG. 1.

The broken lines of the Ratchet Wrench in FIGS. 1-7 are illustrative of portions of the ratchet wrench that form no part of the claimed design.

1 Claim, 6 Drawing Sheets
